LOOM SHUTTLE

John J. Kaufmann, Jr., Greenville, S. C., assignor
to Steel Heddle Manufacturing Company, Phil-
adelphie, Pa., a corporation of Pennsylvania

Application April 12, 1944, Serial No. 530,603

4 Claims. (Cl. 139—220)

1

This invention relates to shuttles for looms, and it relates more particularly to the provision, in automatically threading loom shuttles, of means for minimizing the tendency of the shuttles to become unthreaded or of the filling yarn to become fouled on parts of the threading block during the operation of the loom.

In the shuttles which are used in the modern types of high speed automatic looms, a threading block is usually provided at the rear end of the shuttle. Such threading blocks are made in various shapes and styles and are designed to cause the filling yarn, after an empty bobbin has been displaced and a full one substituted therefor, to be threaded automatically through the threading block, and thence through a side delivery eye, the threading action usually starting on the first pick of the shuttle and being completed on the return pick thereof.

However in the operation of the loom, particularly in the modern high speed looms, there is a tendency of the filling yarn to balloon and to swirl, and also, when reversal of movement of the shuttle takes place, there is sometimes a tendency of the filling yarn to unthread itself by an overcast of the yarn, and this often occurs notwithstanding the threading block is primarily designed to prevent the same.

Furthermore it sometimes happens that when an overcast of the yarn takes place a loop is formed which becomes fouled on one of the parts of the threading block and results in breaking of the filling yarn and consequent stoppage of the loom.

The principal object of the present invention is to provide simple, efficient and inexpensive means for overcoming the tendencies above referred to and to insure proper passage of the filling yarn through the threading block to the side delivery eye.

The nature and characteristic features of the invention will be more readily understood from the following description, taken in connection with the accompanying drawing forming part hereof, in which:

Figure 1 is a top or plan view of the threading end portion of a loom shuttle having a threading block provided with means embodying the main features of the present invention;

Fig. 2 is a longitudinal central sectional view of 50 the portion of the shuttle shown in Fig. 1;

Fig. 3 is a front elevation, enlarged, of the threading block removed from the shuttle;

Fig. 4 is a side elevation, partly in section, and also enlarged, of said threading block; and

2

Fig. 5 is an underneath plan view, also enlarged, of the front end portion of said threading block.

It should, of course, be understood that the description and drawing herein are illustrative merely, and that various modifications and changes may be made in the structure disclosed without departing from the spirit of the invention.

Referring to the drawing, in the particular embodiment of the invention therein shown, the shuttle body 10 is preferably made of wood and has the usual bobbin chamber 11 in which the bobbin 12 is held by the usual means (not shown) whereby it may be readily discharged therefrom and a new bobbin substituted as the filling runs out from time to time.

The shuttle body 10 is also provided with the usual side delivery eye 13 for the passage of the 20 filling yarn 14. The threading block 15 comprises primarily a casting, preferably made of metal, either cast iron or brass, as desired. Said threading block 15 is mounted in a complementally shaped recess 16 in the rear end of the body portion 10 of the shuttle.

The body portion of the threading block 15 is provided with a longitudinal channel 17 through which the filling thread 14 passes to the side delivery eye 13 during the weaving operation.

30 The threading block 15 may be provided with the usual rearwardly extending horn portion 18, and an intermediate horn portion 19 extending into the longitudinal thread channel 17 of the threading block 15, or the threading block may be provided with other similar portions which serve to assist in or bring about the initial threading of the block, as well as the retention of the filling thread therein after the initial threading has been completed.

40 At the front end of the threading block 15, that is the end disposed toward the bobbin, there is provided, on each side of the thread channel 17, a vertical groove or recess 20. Preferably said side recesses 20 extend upwardly from the bottom of the threading block to a point below the top thereof, the casting preferably having a suitable overhang 21 at this point on each side for the purpose of guiding the filling yarn during the threading operation.

In each of the grooves or recesses 20 there is mounted a strip 22 of fur, the hair or fiber of which is of a relatively fine texture. The texture of the fur employed will to a certain extent be dependent on the size of the filling yarn.

55 Advantage is taken of the fact that the fibers

or hair filaments of fur usually extend at an angle of inclination to the skin 23 which carries the same, and the strips 22 of fur are therefore mounted in the recesses 20 on each side of the thread channel 17 with the fibers disposed at a downward inclination (see Fig. 3), and the fibers of each strip 22 of fur are of such length as to extend to and contact with the fibers of the other strip.

By the foregoing arrangement, when the filling is once threaded in the threading block 15, the strips 22 of fur between which the filling yarn 14 passes as it enters the threading block 15 will effectively serve to prevent the filling yarn 14 from being cast out from the entrance end of the threading block 15 either because of the ballooning of the same, or through an overcast when reversal of movement of the shuttle takes place. Also fouling of overcast loops on horn members 18 and 19 of the threading block 15 will be effectively prevented.

I claim:

1. In a loom shuttle having a threading block mounted in one end thereof and provided with a longitudinal thread channel through which the filling yarn passes from the bobbin to the outlet, strips of fur mounted at the entrance end of the threading block, the hair filaments of said fur being disposed at a downward inclination and respectively contacting the hair filaments of the opposite strip.

2. In a loom shuttle having a threading block mounted in one end thereof and provided with a longitudinal thread channel through which the filling yarn passes from the bobbin to the outlet, the threading block having a vertical recess on each side of the thread channel at the entrance end thereof, and strips of fur the skin portions of which are mounted in the aforesaid recesses, and the hair filaments of which extend from the skin on each side at a downward inclination.

3. In a loom shuttle having a threading block mounted in one end thereof and provided with a longitudinal thread channel through which the filling yarn passes from the bobbin to the outlet, the threading block having a vertical recess on each side of the thread channel at the entrance end thereof, and strips of fur the skin portions of which are mounted in the aforesaid recesses and the hair filaments of which are disposed at a downward inclination and respectively contact the hair filaments of the opposite strip.

4. In a loom shuttle having a threading block mounted in one end thereof and provided with a longitudinal thread channel through which the filling yarn passes from the bobbin to the outlet, and a strip of fur mounted at the entrance end of the threading block on at least one side thereof, the hair filament of said fur being disposed at a downward inclination.
